UNITED STATES PATENT OFFICE.

JOHN F. O'CONNOR, OF CHICAGO, ILLINOIS, ASSIGNOR TO WILLIAM H. MINER, OF CHAZY, NEW YORK

DRAFT-RIGGING FOR RAILWAY-CARS.

1,149,399.

Specification of Letters Patent. Patented Aug. 10, 1915.

Application filed May 4, 1914. Serial No. 836,188.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is, to provide a draft rigging of efficient operation.

In the drawings forming a part of this specification, Figure 1 is a side elevation of a draft rigging embodying my invention, and showing the parts in their normal position; Fig. 2 is a plan view partly in horizontal section on line 2—2 of Fig. 1; Fig. 3 is a cross section on line 3—3 of Fig. 2; Fig. 4 is a side elevation partly in central vertical longitudinal section, showing the position of the parts in full buff; Fig. 5 is a perspective view of the front follower; and Fig. 6 is a perspective view of the rear follower.

Referring to the drawings, the numerals 7—7 indicate draft members, or parts of the car-frame to which the draft rigging is applied.

A stationary key 8 is mounted between the draft members, and a coupler key 9 extends transversely of the draft members.

Plates 10—10 are secured to the draft members preferably one along the outer face of each draft member by suitable means, preferably the rivets 11—11. The plates 10 are each provided with a preferably reinforced opening 12 registering with an opening 13 in the adjacent draft member through which an end of the stationary key 8 is received, the said key being secured therein against accidental displacement by suitable means, preferably the bolts 14—14.

Near its forward end, each of the plates is provided with an opening 15 registering with an opening 16 in the adjacent draft member, each of said openings being longitudinally extended to permit forward and rearward travel of the coupler key 9 therein.

A rear follower 17 is slidingly mounted

upon the stationary key 8, and has a pair of spaced-apart forwardly extending arms 18—18 which near their forward ends are 55 provided with the transverse slots 19—19 for the passage of the coupler key 9. The coupler key 9 extends through the draw-bar 20 (only the rear end thereof being shown in the drawings), and the slots 19 in the 60 arms 18 of the rear follower are rearwardly extended to permit the rearward travel of the key 9 therein without buffing strain thereon. The rear follower 17 comprises a vertical plate 21 having at either lateral edge a longitudinal, preferably integral plate 22, each of said plates having preferably integral forward extensions forming the arms 18—18. The rear follower 17 is provided near its rear end with the transverse slot 23, 65 which preferably is longitudinally extended in the plates 22 and the arms 18, and also in preferable construction passes transversely through the plate 21 of the rear follower, the rear end of said slot, through the vertical plate 21, being inclosed by the preferably 70 U-shaped member 24, which is preferably integral with the vertical plates 21 and the longitudinal plates 22.

The slot 23 in the rear follower 17 is longitudinally extended to permit the forward travel of the rear follower upon the key 8 in forward movement of the draw-bar.

The front follower 25 comprises a vertical plate 26 having at either lateral edge a preferably integral longitudinal plate 27, each of said plates being rearwardly extended to form the preferably integral follower arms 28—28. The said arms 28—28 are sufficiently spaced apart to permit the passage between 90 them of the arms 18—18 of the rear follower, the front follower being provided with the spaced-apart longitudinal slots 29—29, there being one for the passage therethrough of each arm 18 of the rear follower. The front follower 25 is also provided with the transverse slot 30, which preferably is formed in the plates 27 and the arms 28 extended therefrom, and above and below the slot 30 the plate 26 of the front follower is provided with a rearwardly extended collar 32, each of said collars being preferably integral with the other parts of the follower, the upper one surrounding the upper spring seat 33

of the front follower, and the lower one surrounding the lower spring seat 34 of the front follower.

Each spring seat is provided with a rearwardly extended boss 35, the rear end of which is in preferable construction in the same vertical plane as the rear faces 36—36 of the collars of the front follower.

The rear follower 17 is provided, both above and below the transverse slot 23, with a forwardly extended collar 37, the upper collar surrounding an upper spring seat 38, and the lower collar surrounding a lower spring seat 39. The collars 37 are preferably integral with other parts of the rear follower, and are partially formed by the longitudinal plates 22—22.

Bosses 40—40 are forwardly extended from each of the spring seats 38 and 39 of the rear follower, the front faces 41 of said bosses being in preferable construction in the same vertical plane as the front faces 42 of the collars of the rear follower.

An upper set of springs 43 is mounted between the upper spring seats of the front and rear followers, and a lower set of springs 44 is mounted between the lower spring seats of the front and rear followers. Each set of springs or compression resisting elements consists preferably of an outer spring 45 and an inner spring 46 nested therein.

An upper bolt 47 passes through the upper bosses of the front and rear followers, having a head 48 engaging against the outer face of the rear follower, and a nut 49 engaging against the outer face of the front follower.

A lower bolt 50 passes through the lower bosses of the front and rear followers, and has a head 51 engaging against the rear follower, and a nut 52 engaging against the front follower.

On rearward movement of the draw-bar, the coupler key 9 travels rearwardly in the slots 19 in the arms 18 of the rear follower 17, the draw-bar forces the front follower rearwardly, the arms thereof sliding rearwardly upon the stationary key 8, the slots 30 in the front follower being sufficiently forwardly extended to permit this movement until the faces of the collars of the front follower engage the collars of the rear follower, and in preferable construction the bosses of the front follower simultaneously engage the bosses of the rear follower while the front end of the transverse slot 30 of the front follower engages against the front edge of the stationary key 8. The front follower in this movement also slides rearwardly upon the forwardly extended arms 18 of the rear follower, which pass through the longitudinal slots 29 in the front follower, and the rear follower is held against rearward movement by the engagement of the stationary key 8 against the forward

ends of the slot 23 through the rear follower, the rear follower thus stopping the rearward movement of the compression resisting members which are compressed between the two followers. On full compression, the parts are in the relative positions illustrated by Fig. 4 of the drawings. On forward movement of the draw-bar, the coupler key 9 is engaged against the forward ends of the slots 19 in the arms 18 of the rear follower, the rear follower is drawn forwardly in sliding movement upon the key 8, compressing the springs against the front follower, the front follower being held against forward movement by the engagement of the rear edge of the stationary key 8 against the rear ends of the slot 30 in the front follower, the arms 18 of the rear follower in this movement sliding forward through the longitudinal slots 29 in the front follower until on full compression of the compression resisting elements between the followers the rear edge of the key 8 engages against the rear ends of the slots 23 in the rear follower, and preferably the collars of the two followers, and the bosses of the two followers simultaneously engage.

I claim:—

1. In a draft rigging for railway cars, draft members, a stationary key extending between the draft members, a front follower having rearwardly extending arms slidably engaging the stationary key, a rear follower slidably engaging the stationary key, a draw-bar, compression resisting elements between the followers, the rear follower having forwardly extending arms passing through the front follower and being slidably connected to the draw-bar, the arms of the rear follower passing between the arms of the front follower.

2. In a draft rigging for railway cars, in combination, draft members, a stationary key extending between said members, front and rear followers slidably mounted upon said stationary key, a draw-bar, and compression resisting members, the rear follower being provided with forwardly extended arms slidably connected to the draw-bar, the compression resisting members being mounted both above and below the stationary key and between the followers, the followers being each provided with slots for the passage of the stationary key, and having co-acting oppositely arranged collars, the compression of the compression resisting elements being limited on movement of either follower by the simultaneous engagement of the key against one end of the slot in the moving follower, and the engagement of the collars of said follower with the collars of the other follower.

3. In a draft rigging of the character described, the combination with draft sills, of a front follower, a rear follower, cush-

ioning means interposed between said followers, the front follower having rearwardly extended slotted arms and the rear follower having forwardly extended arms 5 adapted to be connected to a draw bar, and a stationary key extending through said slotted arms of the front follower, said key being supported between and by said sills.

said key limiting the forward movement of the front follower and the rearward movement of the rear follower. 10

JOHN F. O'CONNOR.
